UNITED STATES PATENT OFFICE.

ALBERT BALL AND THOMAS OFFICER, OF CLAREMONT, NEW HAMPSHIRE, ASSIGNORS TO SULLIVAN MACHINERY COMPANY, OF CLAREMONT, NEW HAMPSHIRE, A CORPORATION OF MAINE.

ENGINE.

No. 842,127.

Specification of Letters Patent.

Patented Jan. 22, 1907.

Application filed March 6, 1905. Serial No. 248,509.

To all whom it may concern:

Be it known that we, ALBERT BALL and THOMAS OFFICER, citizens of the United States, and residents of Claremont, New Hampshire, have invented an Improvement in Engines, of which the following description, in connection with the accompanying drawings, is a specification, like letters on the drawings representing like parts.

Our invention consists in improvements in engines, and more particularly, though not exclusively, in improvements in direct-acting engines of the differential type—such, for example, as are ordinarily employed in connection with rock-drills. This application, so far as it relates to Figs. 1 to 6, inclusive, discloses matter presented in our prior pending application, filed July 26, 1904, Serial No. 218,300.

In the particular embodiment by which we have here illustrated our invention the engine is of the so-called "differential" type employing a constantly-admitted fluid-pressure supplied at one side of the piston, the working stroke of the piston being effected by the intermittent admission of pressure to the opposite side of the piston and there acting upon a greater effective piston area than upon the reverse piston side. Such engines are commonly of the so-called "valveless" type, the admission to and the exhaust from the working end of the cylinder being effected by the uncovering of admission and exhaust ports in the walls of the cylinder. A usual construction is an admission-port to the working end of the cylinder connected by a run-around port with the tool end and a separate exhaust-port.

In prior constructions of differential valveless engines it has been impossible to obtain an effective or prolonged working stroke, owing to limitations which are imposed in the location of the cylinder-ports.

If the exhaust-port is located too near the run-around port, it will be closed too early on the return piston-stroke, and the resulting compression will tend to bring the piston to rest before admission can take place through the subsequent uncovering of the run-around port. If located too remotely from the run-

around port, it will be opened too soon after cut off on the working stroke and before opportunity is given for sufficient expansion of the pressure.

We have shown in the drawings an engine of the direct-acting differential type wherein the admission and exhaust on the working end of the cylinder are controlled by the piston; but additional means are also employed to coöperate with the piston to control the time relation between the exhaust and admission, so that the closing of the exhaust-passage on the return piston-stroke may be materially delayed and herein until the point of admission is reached, the opening of the exhaust-passage on the working stroke being also delayed, if desired, until the piston has reached a point comparatively remote from the exhaust-port, thereby delaying the exhaust and permitting any desired degree of expansion to take place. Through our invention the exhaust-port may be located, if desired, at the end of the cylinder and with cut reference to the run-around port, and the length and effectiveness of the piston-stroke may be very greatly increased.

Our invention will be best understood from the following description, when taken in connection with the accompanying illustrations of one specific embodiment thereof, while its scope will be more particularly pointed out in the appended claims.

In the drawings, Figure 1 is a central longitudinal section taken through the engine-cylinder, showing one position of the piston. Fig. 2 is a similar view showing another position of the piston. Fig. 3 shows a modified form of auxiliary valve. Fig. 4 is a plan view of the cylinder-casting, showing the air-passages. Fig. 5 is an elevation showing the connection and relation of the engine illustrated in the preceding figures to its supporting-frame. Fig. 6 is a fragmentary view looking from the rear of Fig. 5 to show the pressure-supply conduit. Fig. 7 is a sectional view of the engine-cylinder, showing a modified arrangement of the exhaust-passage, and Fig. 8 is an end view of the same.

Referring to the drawings, and particularly to Figs. 5 and 6, the cylinder A of the engine

embodying the illustrated form of my invention is connected with the frame-rods b b by laterally-extending ears a a . The cylinder, with the drill-tool c , may be slid lengthwise of the said rods to feed the tool toward and from the work by rack-and-pinion feeding mechanism B , operated through hand-lever d . The arrangement and relation of these parts form no part of the invention claimed in this application, and so far as they present features of novelty they are referred to and claimed in our aforesaid prior application.

At the uppermost end of the supporting-frame is a holding member e , provided with a conduit for receiving the supply of fluid under pressure, which herein is assumed to be air. During the operation of the drill air is supplied through suitable connections from the source of supply (not shown) to the mouth e' of the holding member, thence to the depending leg e^2 , its admission to the passage therein being controlled by the rotary hand-valve f , so located as to be conveniently manipulated by the thumb and finger of that hand grasping the said holding member. From the leg e' it passes into a chamber in the offset portion e^3 and thence through a stationary pipe e^4 , Fig. 6, to the pressure-chamber e^5 of the engine-cylinder. In entering the pressure-chamber the pipe e^4 passes through a suitable stuffing-box and is extended into the chamber for a sufficient length to permit the necessary movement of the cylinder to take place along the rods b b during the feeding of the drill.

Referring now more particularly to the internal construction of the engine-cylinder, the latter is provided with cylinder-heads g g' , which, together with the tie-rods g^2 g^2 and the recoil-springs g^3 g^3 , employed yieldably to draw the cylinder-heads together, are of a construction usual in this class of apparatus.

Referring to Figs. 1, 2, and 4, the air is constantly admitted to the cylinder through the open passage g^4 from the pressure-chamber e^5 , tending thereby to return the piston to the position shown in Fig. 1. On its upward travel the piston uncovers the run-around port h , admitting air, as afterward described, through the port h' to the working end of the piston. The latter having greater effective working area than that of the tool end of the piston, the momentum of the upwardly-moving piston is overcome and the drill starts on its reverse working stroke. Interposed between the ports h and h' is a differential piston-valve h^2 , having a head h^3 , slideable in a cylindrical chamber h^4 , the opposite end of which is connected with the air-chamber e^5 through a passage h^5 . The differential valve h^2 at the commencement of the working piston-stroke is held in the position shown in Fig. 1 by the pressure admitted through the port h , which, acting on the head h^2 of greater area, overcomes the pressure ad-

mitted through the duct h^5 , the latter acting on the head h^3 of relatively smaller area.

The valve h^2 will be maintained in the position shown in Fig. 1 on the working stroke of the piston until the latter has traveled far enough to expand the working fluid below a critical point, such that the pressure acting on the head h^3 is no longer sufficient to overcome that acting upon the head h^2 . When this point is reached, the valve moves to the position shown in Fig. 2, intercepting communication between the ports h and h' and opening the latter to the exhaust-passage h^6 , thereby permitting exhaust from the working end of the cylinder. The critical point determining the timing of the exhaust will obviously depend upon the relative areas of the differential heads h^2 and head h^3 . Increasing the difference in the areas will retard the opening of the exhaust-passage and prolong the piston-stroke, while decreasing the difference in the two areas will advance the exhaust and shorten the piston-stroke. By suitably proportioning the differential valve the stroke of the piston may be varied within wide limits.

After exhaust has taken place and the momentum of the piston overcome the upward stroke of the piston commences, but the valve h^2 remains in the position shown in Fig. 2 to permit exit from the cylinder of the air in front of the upwardly-moving piston until the piston has moved past and uncovered the port h , whereupon the live pressure admitted thereto forces the differential valve h^2 upward into the admission position shown in Fig. 1, closing the exhaust-passage and permitting the live pressure in the run-around to enter the working end of the cylinder through the port h' . The piston continues moving upward until the momentum has been overcome and then returns on the working stroke, as before described.

Although it is unnecessary for the operation of the engine in practice, we prefer to connect the cylinder to the port h by means such as the vent-opening h^7 , since we have found that continued use is apt to cause such wear that a leakage from the tool end of the cylinder to the port h will sometimes occur before the latter has been actually uncovered by the piston on its upward stroke, with the result of prematurely raising the piston-valve h^2 to its admission position. The vent-opening h^7 equalizes the pressure in the port h with the pressure in the working end of the cylinder until the port h is uncovered. Immediately after this the vent-opening itself is closed by the upward travel of the piston. By the use of the auxiliary or differential valve shown the several events of the piston-stroke are controlled by the piston, as is usual with a differential engine; but the actual timing of the exhaust is controlled through the coöperation of the piston with the

run-around port h instead of, as heretofore, through the actual covering or uncovering of the exhaust-port h by the piston.

Although in practice we prefer to employ differential fluid-pressures, as described, for operating the controlling-valve, since variations in one pressure are substantially neutralized by variations in the other, nevertheless any suitable means for differentially acting upon the valve may be employed.

In the form of auxiliary valve shown in Fig. 2 the valve when in the exhaust position rests upon the stop h^8 and in that position is therefore subject to a lesser pressure than when lifted into the position shown in Fig. 1, where a greater area is exposed to the lifting-pressure. In Fig. 3 we have shown a modified form of valve, which is similar to that shown in Fig. 2, but provided in place of the stop h^8 with a plunger h^9 , which moves within the vented chamber h^{10} . This maintains constant the effective area of the valve exposed to pressure admitted to the port h and insures quicker closing of the valve when once the pressure in the port h has been reduced.

In Figs. 7 and 8 we have shown a modified arrangement of discharge-passages for the exhaust. The exhaust-passage h instead of leading directly into the atmosphere discharges into the chamber k , formed by the surrounding shell k' . The exhaust passes downward into the annular chamber k^2 , surrounding the piston, and is discharged to the annular opening k^3 down and about the exposed body of the piston-rod at the point where it enters and leaves the cylinder stuffing-box. This arrangement keeps the exposed portion of the piston-rod free from the dirt and dust which the cutting-tool throws up and the piston-rod tends to pick up in its reciprocation. It also utilizes particles of oil which are inevitably carried out with the exhaust by causing them to impinge on the piston-rod and to be used in lubricating the same.

The lip k^4 projects beneath the discharge-opening k^3 and partially encircles the piston-rod at the side on which the operator stands in order to prevent the discharged exhaust from spreading in his direction.

In the modification illustrated the nose of the cylinder-casting is shown as formed in a separate piece k^5 , and the piston-packing k^6 is compressed between a shoulder in the said nose and a gland k' , the whole forming a simple and effective stuffing-box when the nose k^5 is bolted to the cylinder-casting.

We here deem it unnecessary to refer to the various modifications in form, details, and arrangement of parts which may be made in the form of our invention here disclosed and which will be obvious to those skilled in the art, nor do we deem it necessary to refer to the various obvious applica-

tions which may be made of our invention other than those here referred to, but have in accordance with the requirements illustrated our broad invention by a single specific embodiment thereof and a single particular application.

We claim—

1. An engine provided with a cylinder and a piston movable therein, one side of said piston being in constant communication with the source of fluid-pressure supply, and a valve-controlled port in the cylinder-walls communicating with the other side of said piston, said port being opened by the piston to admit pressure to the rear end of the cylinder on rearward movement of the piston and closed thereby in its movement in the other direction.

2. A differential engine having constantly-admitted pressure at one side of the piston and a differential valve having constant pressure upon a pressure area thereof, but adapted to be moved by pressure admitted from the constant-pressure end of the cylinder and under control of the piston for admitting pressure to the opposite side of the piston.

3. A differential engine having a constantly-admitted pressure at one end of the cylinder, a piston-controlled port at the admission end thereof and communicating with the opposite end thereof, a differential valve in said port and an exhaust-port for the opposite cylinder end, said piston-controlled port and exhaust-port being separated by a space at least as great as the length of the piston.

4. An engine provided with a cylinder and a piston movable therein, a cylinder-port controlled by said piston means for admitting fluid-pressure to one side thereof, an exhaust-passage for the opposite piston side, and a differentially-controlled valve for alternately connecting said opposite side to said cylinder-port and said exhaust-passage.

5. A direct-acting engine provided with a differential piston, the smaller area of which is subject to a constantly-acting pressure, a pressure-passage leading from the constant-pressure end of said cylinder to the opposite end thereof, a differential valve controlling said passage, the smaller area of said valve being exposed to a constant pressure and tending to move the valve to a position exhausting pressure from the larger piston area and closing the same to the pressure-passage, and the larger area of said valve being exposed to the pressure admitted to said pressure-passage.

6. A direct-acting engine having a differential piston provided with a relatively large area at the head end of the cylinder and a relatively small area at the tool end thereof and having a constantly-admitted pressure acting upon the smaller area, a port adapted to

- be opened to the pressure on rearward piston movement and closed thereto on forward movement thereof, a passage connecting said port with the head end of the cylinder, a differential valve controlling said passage and presenting its larger area to the pressure intermittently entering said passage and having its smaller area subjected to a constant pressure, and an exhaust-passage also connected with the head end of said cylinder, said valve being normally held by the constant pressure to open the head end of said cylinder to said exhaust-passage and close the same to said connecting-passage, but intermittently moved to close the said exhaust and admit pressure to the head end of said cylinder.
7. An engine having a differential piston, means for constantly admitting pressure to the smaller area thereof, a pressure-passage connecting the constant-pressure cylinder end with the opposite end thereof, said passage being opened or closed to pressure by movement of the piston, a differential valve controlling said passage, an exhaust-passage for said opposite cylinder end, and means dependent upon the expansion of the pressure on movement of the piston toward the constant-pressure cylinder end for opening the said exhaust-passage.
8. A direct-acting engine provided with a cylinder having a differential piston, means for constantly admitting pressure to the smaller area of said piston, a passage formed in the cylinder-wall and connecting the opposite ends of said cylinder, and a differential valve in said passage, said piston on movement in one direction being adapted to open said passage to the pressure and move said valve to admit motive fluid to the opposite cylinder end, and upon its opposite movement to cut off fluid-pressure from said passage and permit said valve to be shifted to open said opposite cylinder end to the exhaust.
9. A direct-acting engine provided with a differential piston having pressure constantly admitted to the smaller area thereof, a passage connecting the opposite ends of the cylinder for the intermittent admission of pressure to the larger piston area, and a valve in said passage, said piston on movement in one direction being adapted to open said passage to pressure and to move said valve to admit pressure to the intermittent-pressure end of said cylinder, and on movement in the opposite direction to close said passage to pressure and permit movement of the valve in the opposite direction to open the said intermittent-pressure cylinder end to the exhaust.
10. A direct-acting engine provided with a differential piston, the smaller area of which is subjected to a constantly-acting pressure, a pressure-passage leading from the constant-pressure end of said cylinder to the opposite end thereof, a differential valve controlling said passage and constantly pressed toward a position where it acts to exhaust pressure from the larger piston area while closing the same to said pressure-passage, the larger area 70 of said valve being exposed to the pressure admitted to said pressure-passage.
11. A direct-acting engine having a differential piston provided with a relatively large area at the head end of the cylinder and a relatively small area at the tail end thereof, and having a constantly-admitted pressure acting upon the smaller area, a port adapted to be opened to the pressure on rearward piston movement and closed thereto on forward movement thereof, a passage connecting said port with the head end of the cylinder, a differential valve controlling said passage and presenting its larger area to the pressure intermittently entering said passage, and an exhaust-passage also connected with the head end of said cylinder, said valve being constantly pressed to open the head end of said cylinder to said exhaust-passage and to close the same to said connecting-passage, but intermittently moved through the pressure admitted to said connecting-passage to close the said exhaust and admit pressure to the head end of said cylinder.
12. A direct-acting engine provided with a cylinder having a differential piston having a constant-pressure area, a passage formed in the cylinder-wall and connecting the opposite ends of said cylinder, a differential valve in said passage, said piston on movement in one direction being adapted to open said passage and move said valve to admit fluid-pressure through the valve and passage to one end of said cylinder and upon its opposite movement to cut off fluid-pressure from said passage and permit said valve to be shifted to open said cylinder end to the exhaust.
13. An engine having a differential piston and provided with means for constantly admitting pressure against the smaller piston area, a port adapted to be opened to the pressure on piston movement in one direction, but closed thereto on movement in the opposite direction, a passage connecting said port with the opposite end of the cylinder, a differential valve controlling said passage and presenting its larger area to the pressure intermittently entering said passage and having its smaller area subjected to a constant pressure, and an exhaust-passage also normally held by the constant pressure to open said cylinder end to the exhaust-passage and close the same to said connecting-passage, but intermittently moved to close the said exhaust and admit pressure to the said 115 cylinder end.
14. An engine provided with a cylinder, a piston, means for constantly admitting pressure to one end of said cylinder, a pressure-passage connecting said constant-pressure 120
- 65 130

cylinder end with the opposite cylinder end for the intermittent admission of pressure thereto, a valve controlling said passage and having a pressure area alternately exposed to the constant-pressure side of the piston and the intermittent-pressure side thereof.

In testimony whereof we have signed our

names to this specification in the presence of two subscribing witnesses.
